a corporation of New York

Application May 10, 1933, Serial No. 48,064

Term of patent 3½ years

To all whom it may concern:

Be it known that I, PAUL E. SILLIERE, a citizen of the United States of America, and residing at New York city, in the county of Bronx, and State of New York, have invented a new, original, and ornamental Design for a Textile Fabric, of which the following is a specification, reference being had to the accompanying drawing, forming part thereof.

The figure in the drawing is a plan view in full size showing the details of the design, a complete repeat unit thereof being shown.

I claim:

The ornamental design for a textile fabric substantially as shown and described.

PAUL E. SILLIERE.
